UNITED STATES PATENT OFFICE.

HENRY GEORGE EDMUND REYNOLDS, OF SUMMERLAND, BRITISH COLUMBIA,
CANADA.

COMBINATION MATCH SAFE AND ASH TRAY.

Application filed May 12, 1924. Serial No. 712,853.

To all whom it may concern:

Be it known that I, HENRY GEORGE EDMUND REYNOLDS, a subject of the King of Great Britain, and a resident of Summerland, in the Province of British Columbia, Canada, have invented certain new and useful Improvements in Combination Match Safes and Ash Trays, of which the following is a specification.

10 My invention relates to improvements in combination match safes and ash trays, the objects of which are to provide a convenient means for containing matches and cigarette or cigar ashes, which may be attached 15 to a vertical surface such as the windshield of a motor car, to provide means whereby the matches can be easily placed into or withdrawn from the match safe, to provide for an automatic closure for the ash tray 20 and means for its removal for emptying when desired.

The invention consists essentially of a container having vacuum cups for its attachment to the windshield within which 25 a removable ash tray is carried, and a match safe pivotally mounted in the container, as will be more fully described in the following specification, in which:—

Fig. 1 is a section taken on the line 1—1 of 30 Fig. 3.

Fig. 2 is a side view showing the container opened for the removal of the ash tray.

Fig. 3 is a front view.

In the drawings like characters of reference indicate corresponding parts in each figure.

The numeral 1 indicates generally the container having a pair of side walls 2 and a bottom wall 3; the side walls are connected together at their upper rear corners by a rod 4 upon which a rear wall 5 is hinged. The rear wall 5 is provided with a plurality of vacuum cups 6 by which it is secured to the glass of the windshield 7, and at the 45 lower extremity of the rear wall a spring tongue 8 is formed which is adapted to engage a projection 9 for the purpose of holding the container in closed position.

The numeral 10 indicates a cover which is 50 pivotally mounted to the side walls 2 as at 11 and is weighted as at 12 to restore the cover to a closed or horizontal position after use. In the rear half of the container an ash receptacle 13 is placed which may be 55 readily withdrawn for emptying the ashes

when the container 1 is tilted forwardly and upwardly as shown in Fig. 2.

The numeral 14 indicates generally a match safe having a front wall 15 which is provided with a vertical slot 16 through 60 which the matches carried in the safe are exposed to view, a serrated strip 17 is impressed in the front wall 15 to form a striker for the matches. The match safe 14 is pivotally mounted to the side walls 2 as at 65 18 and is provided with a weighted floor 19 for the purpose of drawing the safe back into the container after use; in order that the safe may be prevented from too great a forward movement a pair of pins 20 extending 70 inwards from the side walls 2 are placed to engage the stops 21 of the match safe side walls 22; the rear wall 23 is carried to a similar height to the front wall so that the rear edge of the weight 12 upon the cover 10, 75 when the cover is in closed position, overhangs the rear wall to prevent the match safe from forward or opening movement.

Having thus described the several parts of my invention I will now briefly explain 80 the manner in which it is used.

When it is desired to fill the match safe the forward portion of the cover 10 is raised and matches are placed therein; to remove a match the cover is raised and the 85 match safe tilted forward; a match is then gripped between the forefinger and the thumb, the thumb engaging the match through the slot 16 of the front wall 15. When a match has been withdrawn from 90 the safe, the weighted floor 19 withdraws the match safe 14 into position within the container, the upper end of the rear wall 23 striking the weight 12 and tilting the cover 10 which falls back into closed position when the match safe becomes restored to its normal position.

To deposit ashes into the ash receptacle 13 it suffices to depress the rear end of the cover 10 with the burning end of the cigarette or cigar to form an inclined runway when the ash is broke off and allowed to slide down the runway into the ash receptacle. When the pressure on the cover is removed it resumes its horizontal position, leaving the ashes contained in the receptacle immune from disturbance from wind or other causes.

What I claim as my invention is:

1. A device of the class described com-

- prising a main container, a match safe the match safe and ash receptacle and pivotally mounted in the main container adapted when closed to hold the match and an ash receptacle carried within the safe in the inwardly withdrawn position. 25
- 5 5 from, a pivotally mounted cover for both the match safe and ash receptacle adapted to swing outward from the container when the cover is tilted, and means for returning the match safe into the container after use.
- 10 2. A device of the class described comprising a main container, a match safe mounted to swing outward from the main container, an ash receptacle, a stop carried by the container for limiting the outward 15 movement of the match safe, and a common cover for the match safe and ash receptacle.
3. A device of the class described comprising a main container, a match safe pivotally mounted in the main container 20 to swing forward, an ash receptacle also contained within the main container, a pivotally mounted cover common to both
4. A device of the class described comprising a main receptacle, a match safe pivotally mounted within the main receptacle to swing forward at its upper end, means for automatically returning the 30 match safe from its inwardly swung position after use, an ash receptacle contained in the main receptacle, a common cover for the match safe and ash receptacle, and means for permitting the withdrawal of the ash 35 receptacle rearward from the container and the match safe forward from the container.

Dated at Summerland, British Columbia, Canada, this 2nd day of May, 1924.

HENRY GEORGE EDMUND REYNOLDS.
